Hanson & Hanson

UNITED STATES PATENT OFFICE.

RICHARD P. COLLINS, OF NORWOOD, PENNSYLVANIA.

DETACHABLE HANDLE FOR CUTTERS, &c.

1,357,763.

Specification of Letters Patent. Patented Nov. 2, 1920.

Application filed March 15, 1918. Serial No. 222,604.

To all whom it may concern:

Be it known that I, RICHARD P. COLLINS, a citizen of the United States, and a resident of Norwood, county of Delaware, State 5 of Pennsylvania, have invented certain Improvements in Detachable Handles for Cutters, &c., of which the following is a specification.

The object of my invention is to provide 10 means for holding a cutter used for metal working and to provide a detachable handle, which will rigidly hold the cutter and which can be readily detached or applied.

In the accompanying drawings:

15 Figure 1 is a perspective view of my improved handle, showing it applied to the cutter;

Fig. 2 is a side view, partly in section;

Fig. 3 is a plan view, partly in section;

20 Fig. 4 is a perspective view of the hinged strap by which the handle is secured to the cutter;

Fig. 5 is a detached perspective view of 25 a plate with the reinforcing spindle for the handle;

Fig. 6 is a perspective view of one form of cutter; and

Fig. 7 is a view illustrating a modification of the invention.

30 1 is the cutter which, in the present instance, is rectangular in cross section and has a sharp edge 2 and is for the purpose of cutting the metal in steel and iron mills and foundries. The flat surface of the cutter is used as a head against which a sledge 35 strikes. The handle 6 is for the purpose of allowing one man to hold the cutter while another strikes a blow with a sledge. The usual method of making these cutters is to 40 form an eye in the center through which the handle extends. This weakens the cutter to such an extent that it often breaks at the eye so that the tool has to be discarded.

45 By my invention, I form an annular recess 3 at the center of the cutter, leaving the body portion solid so as to resist the blows. I provide a strap 4 of a thickness, in the present instance, equal to the depth 50 of the recess 3 and this strap engages the cutter on three sides, as clearly shown in Fig. 3. The strap is made in two parts and is connected together at the front by a hinge 5 so that it can be opened, as clearly 55 shown in Fig. 4. The strap is turned in, as at 7, so as to form shoulders at the back

of the cutter, and located between the shoulders 7 and the cutter is a plate 8, which snugly fits the recess at the back of the cutter and has a spindle 9, which extends into 60 the handle 6. This spindle not only holds the plate, but also reinforces the handle. The strap 4 has extensions 10, which are curved, as shown, to fit the handle 6 and in each extension is a slot 11 for the reception of a transverse bolt 12, which passes through an opening 13 in the handle and through an opening 14 in the spindle 9, and is provided at its opposite end with a wing nut 15. Washers are used between the head 65 of the bolt and one extension of the strap and a washer is also used between the wing nut 15 and the other extension. In the present instance, the bolt snugly fits the opening in the handle and in the spindle 9 70 and is adjustable in the slots of the extension so that in applying the handle to the cutter, it is pushed against the cutter until the plate 8 is in contact with the cutter, then the strap is secured to the handle by 75 a transverse bolt 12.

In some instances, the plate 8 and spindle 9 may be omitted, as shown in Fig. 7, and in this instance the end of the handle 6^a is brought in contact with the side of the 80 cutter and the inturned flanges 7^a rest directly against the back of the cutter. In this particular instance, the recess in the cutter only extends at the front and each side. This adds strength to the cutter, as 85 the back is not recessed.

I preferably so design the strap that the diameter of the space between the extensions is greater than the diameter of the handle, so that when the nut is turned to 90 bring the extensions onto the handle, the strap is also firmly clamped to the cutter.

In assembling the tool, the strap 4 is placed on the cutter and the handle, with the plate placed in the recess at the back 100 of the cutter and forced against the cutter. The bolt is passed through the several openings and then clamped tightly, making a firm connection between the handle and the cutter.

105 While I have illustrated my invention as applied to a particular form of cutter, it will be understood that the shape of the cutter will vary according to the use for which it is intended and though it is particularly adapted for holding cutters, it can be used for holding hammer heads, picks,

and like objects to which a handle is secured.

I claim:

1. The combination of a cutter, said cutter being recessed on a plurality of its sides; a strap made in two sections and adapted to enter said recesses; said sections having rearward extensions shaped to conform to a handle; inturned ears on the 10 strap bearing against the back of the cutter; a handle extending between the extensions and adapted to be engaged thereby; and means extending through the handle and through the extension adapted to clamp 15 the extensions to the handle.

2. The combination of a cutter having a recess on all four sides; a two-part strap shaped to fit the recess, the two parts of the strap being connected together by 20 hinges at the front, each section of the strap having an extension; a handle located between the extensions, said extensions being shaped to fit the handle; a transverse

bolt for securing the extensions to the handle; and inturned flanges on the strap located at the back of the cutter. 25

3. The combination of a cutter having a recess extending on all four sides thereof; a handle; a longitudinal opening in the handle; a plate at the end of the handle 30 having a spindle adapted to the opening in the handle, the plate extending into the recess in the rear of the cutter; a transverse opening in the handle and in the spindle; a strap located in the recess in three sides 35 of the cutter, said strap having extensions shaped to conform to the shape of the handle, said extensions being slotted; a bolt extending through the slots in the extensions and through openings in the handle 40 and the spindle; and a nut on the bolt for drawing the extensions tightly on the handle and against the sides of the cutter.

In witness whereof I affix my signature.

RICHARD P. COLLINS.
